UNITED STATES PATENT OFFICE.

ROBERT D. GREGG AND FRANK L. SHIDLER, OF KANKAKEE, ILLINOIS.

LONGITUDINAL JOINT FOR CONCRETE ROADWAYS.

Application filed May 27, 1927. Serial No. 194,583.

This invention relates to that class of concrete roadways, in which the roadway is formed in sections of slabs of an approved size and separated by transverse expansion joints in connection with a central longitudinal joint providing a flexible or hinge connection at the crown or center of the roadway, examples of which are set forth in our prior Letters Patent No. 1,604,990, and 1,604,991, dated Nov. 25, 1926, and the present improvement has for its objects:—

To provide a structural formation and association of parts in the above mentioned type of longitudinal joints of concrete roadways whereby an interlocking connection is provided at central or other longitudinal joint of the roadway and preferably of a limited hinge or flexible nature, with such interlocking connection of parts of sufficient strength to tie the roadway sections or slabs together against any tendency to move apart or separate, as well as to resist shearing action caused by heavy traffic.

To provide a simple and efficient means whereby the above mentioned interlocking connection of the roadway sections or slabs is attained by a series of cup shaped shells, preferably of an oblate spheriodal form, fixed in place in an edge of the roadway section or slab and adapted to be filled with the concrete mass of an adjoining roadway section or slab to form the interlocking means between the sections, during the serial operation of forming the roadway sections or slabs, all as will hereinafter more fully appear.

In the accompanying drawing:

Fig. 1, is a detail transverse section showing the preferred form of the present invention as applied to the longitudinal center joint of a sectional concrete roadway.

Fig. 2, is a similar view illustrating the means where the cup shaped shells of the present interlocking connection are placed in the edge of a roadway slab or section.

Fig. 3, is a detail transverse section, similar to Fig. 1 showing a parting strip that supports the series of interlocking joint forming cups or shells, is left as an imbedded portion of the roadway.

Fig. 4, is a detail elevation of an end portion of the parting strip shown in Fig. 4.

Fig. 5, is a detail section illustrating a modified means of attachment of the holding means of the cup shaped shells of the invention.

Like reference numerals indicate like parts in the several views.

The present improvements are more especially adapted for use in the formation of concrete roadways of the sectional or slab type, and comprises means, and the use and application, to form an interlocking connection, preferably of the flexible or hinge type, between the longitudinal edges of the roadway sections or slabs. Such application involving the formation and normal setting or hardening in place of one concrete roadway section or slab, before an adjoining and succeeding section or slab is formed in abutting relation to the first mentioned section or slab.

In the practical application of the invention and in the preferred manner indicated in Figs. 1 and 2, a form or mold board 1 of either wood or metal, is properly anchored in place to constitute a wall of the cavity in which the concrete roadway slab or section 2 is molded. Such board carries at or near its mid-height a series of cup shaped shells 3, preferably of the oblate spheriodal form shown, and in which the mouth or opening of each shell is of a less diameter than that of the interior of the shell. The shells 2 are secured in spaced relation along the length of the mold board 1, usually twelve inches apart, and the preferred constructions are detachably connected to said mold board, so that the same may be subsequently removed leaving the series of shells 3 fixed in the mass of concrete forming the roadway slab or section 2 which has just been molded. In this form of the invention each shell 3 is held in place in the stated detachable manner by a prolate shaped shell 4 secured by bolts 5 to the mold board 1, with the open mouthed end of an aforesaid oblate spheriodal cup shaped shell 3 adapted to be snapped over a holding shell 4 to provide the required detachable engagement between the parts.

It is within the scope or province of this part of the invention to secure the shells 3 in place on the board 1 by other ordinary detachable connecting means, such for instance as by means of a headed nail 6 passing through the crown or central portion of the shell and driven into the mold board 1 as shown in Fig. 5, with the head of said nail adapted to be torn out of the wall of the shell in the subsequent removal of the mold board and leaving the shell 3 in the con-

crete section or slab 2. Usually the margin of the opening in the shell 3 for the nail 6 will be weakened in any usual manner to permit ready tearing apart of the shell wall 5 and nail head above referred to.

With the above described construction, no parting strip is employed and the concrete mass of one roadway section or slab 1, is in direct contact with an adjacent section or 10 slab.

When however a parting strip is desired at such point, the same is provided by a plate or strip 7 adapted to remain in place after the molding of adjacent roadway slabs 15 or sections, with said parting strip 7 consisting of a plate or strip of metal or like material formed with a series of orifices 8 along its length and near its mid-height, with the margin of each of the openings 8 20 formed with a cluster of retaining prongs 9 and boss 10, adapted to engage an out turned marginal rim 11 at the mouth or opening of a cup shaped shell 3, as illustrated in Figs. 3 and 4. With such constriction the concrete material of the roadway section or 25 slab last formed is adapted to enter through the openings or orifices 8 of the parting strip 7 and the aligned mouth or orifices of the cup shaped shells 3, to fill the interior of 30 said shells and constitute the interlocking connections of the present invention.

In the practical carrying on of the invention, and with the form or mold board 1 in place and carrying the series of cup shaped 35 shells 3, the concrete section or slab is poured or molded in the forming cavity and around said shells as illustrated in Fig. 2. At the end of about twenty four hours for the hardening of the poured mass of concrete, the 40 form or mold board 1 can be safely stripped off, leaving the series of cup shaped shells 3 securely imbedded in the concrete mass of the section or slab just formed. In that it has been from a number of actual tests that 45 the joint formed by a cup shaped shell 3, two and one-half inches in diameter will withstand a pulling stress of three hundred

pounds at the end of twenty four hours after having been set in a concrete mass, there is little if any liability to pulling out 50 when the form board 1, is taken away. It has also been found that the shearing strength of the ball like portion of the present interlocking construction is more than five thousand pounds for a 1-2-3, mixture, 55 and consequently the roadway sections or slabs will be maintained at a uniform elevation under heavy traffic or frost actions.

Before the next adjacent roadway section or slab is molded, the one previously molded 60 should have its vertical edge coated with a heavy oil or like repellent substance, with a view to render the joint or seam both waterproof and flexible. And with a view to aid in such flexibility in the joint the interior 65 surface of the cup shaped shells 3, should be sprayed or coated with such heavy oil or like repellent substance, in order to avoid adhesion.

By placing the cup shaped shells 3 in the 70 longitudinal marginal edges of a concrete roadway, provision is made for the subsequent formation of added lateral sections or slabs, and their effective attachment to the roadway already formed, when an increase 75 in traffic required a widening of the roadway.

Having thus fully described our invention what we claim and desire to secure by Letters Patent, is:—

A longitudinal joint for sectional concrete roadways, comprising a series of cup shaped shells molded in a vertical edge of a roadway section, the entry mouth of each shell being of a less diameter than its interior, the interior of said shells adapted to be filled through the entry mouths with the concrete material of a subsequently formed adjoining roadway section to provide an interlocking joint between said sections.

In testimony whereof we affix our signatures.

ROBERT D. GREGG.
FRANK L. SHIDLER.
